UNITED STATES PATENT OFFICE.

EMANUEL NELSON AND ADOLPHUS ADDISON BASSETT, OF GLENDALE, CALIFORNIA.

DUST CAP.

Application filed October 31, 1924. Serial No. 747,039.

To all whom it may concern:

Be it known that we, EMANUEL NELSON and ADOLPHUS ADDISON BASSETT, citizens of the United States, residing at Glendale, in the county of Los Angeles and State of California, have invented certain new and useful Improvements in a Dust Cap, of which the following is a specification.

This invention relates to improvements in dust caps for the valve stems of pneumatic tires and has for its principal object to provide a simple and efficient means whereby the cap may be readily moved out of engagement with the upper end of the usual valve stem to permit the attachment of an inflating pump to the valve without necessitating the entire removal of the dust cap from the valve stem.

A further object of the invention is to provide a dust cap of the above mentioned character, wherein means is associated therewith for preventing any foreign substance from coming in contact with the upper end of the valve stem when the cap is in its normal position on the stem.

A still further object of the invention is to provide a dust cap of the above mentioned character, which is of such construction as to prevent the accidental displacement of the dust cap such as frequently occurs when the dust cap is removed and the pneumatic tires of an automobile are being inflated.

A still further object of the invention is to provide a dust cap of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a side elevation of the dust cap embodying my invention showing the same in position on a valve stem.

Figure 2 is a similar view taken at right angles thereto, and

Figure 3 is a vertical sectional view thereof.

In the drawing wherein for the purpose of illustration is shown the preferred embodiment of my invention, the numerical 1

designates a supporting sleeve, the lower end thereof being internally threaded as illustrated at 2 for engagement with the usual valve stem 3. The lower end of the sleeve 1 is adapted to engage the usual locking nut 4 threaded on the valve stem 3. Extending laterally from the upper portion of the sleeve 1 at diametrically opposite points are the pins 5 and 6 respectively. The upper end of the sleeve 1 terminates at a point below the upper end of the usual valve stem 3 in the manner clearly illustrated in Figure 3 of the drawing.

Cooperating with the sleeve 1 is the cap member 7. The lower portion of the cap 7 is cut away as illustrated at 8 to provide a pair of diametrically opposed ears 9 and 10 respectively. The ears 9 and 10 of the cap 7 fit over the sleeve 1 and formed in each of the ears is a longitudinally extending slot 11 which terminates at its upper end in the lateral slot 12, the end of which terminates in the downwardly extending notch 13. The provision of the bayonet slots in the ears of the lower portion of the cap 7 provides a means for cooperation with the laterally extending pins 5 and 6 whereby the cap 7 is adapted for slidable as well as pivotal swinging movement with respect to the sleeve.

When the cap 7 is in its normal position on the sleeve 1 in the manner shown in the drawing, the pins 5 and 6 on the upper portion of the sleeve 1 will be seated in the notches 13 formed in the respective ears of the cap whereby the cap is normally locked in a closed position over the upper end of the valve stem. To further prevent any foreign substance from gaining access to the valve in the upper portion of the valve stem, a rubber cover 14 which is supported in the metallic receptacle 15 is disposed over the upper end of the valve stem and normally held in engagement therewith by means of the coil spring 16, one end of

which engages the top of the cap 7 and the other end being in engagement with the metallic receptacle 15 in the manner clearly shown in Figure 3. The rubber cover 14 has its central portion provided with a depression to prevent the air within the pneumatic inner tube from being released when the cap 7 is in position over the upper end of the valve stem.

When it becomes necessary to inflate the inner tube of a pneumatic tire by attaching

2
an inflating pump end of the valve stem, the cap 7 is disengaged from its normal position by actuating the cap in such a manner as to cause the pins to be moved out of engagement with the notches 13 and the lateral slots 12 so that the pins will be disposed within the upper portion of the longitudinally extending slots 11. By releasing the pressure on the upper end of the cap 7, the coil spring 16 which is normally compressed will assist in causing the cap 7 to move upwardly with respect to the sleeve and when the pins 5 and 6 are in the lowermost ends of the slots 11, the cap 7 may then be swung into the position as shown in the dotted lines in Figure 1 whereby the same will uncover the upper end of the valve stem and permit the attachment of an inflating pump thereto. This construction permits the dust cap 7 to be swung out of the way yet supported by the sleeve in such a manner as to prevent the accidental displacement of the cap during the inflation of the inner tube of a pneumatic tire. After the inner tube has been properly inflated, the dust cap 7 is again moved to its normal position over the upper end of the valve stem.

It will thus be seen from the foregoing description, that a dust cap for valve stems has been provided which is of such construction as to save considerable time and labor in disengaging the dust cap from the valve stem whenever it becomes necessary, means being further provided for normally locking the dust cap in position over the valve stem against accidental displacement therefrom.

While we have shown the preferred embodiment of our invention, it is to be understood that various changes in the size, shape

and arrangement of parts may be resorted to without departing from the spirit of the invention and the scope of the appended claims.

Having thus described the invention, what we claim is:—

1. A dust cap comprising a sleeve threaded at its lower end on the usual valve stem, laterally extending pins at diametrically opposite points on the upper portion of the sleeve, a cap member, ears on the lower portion of the cap at diametrically opposite points, said ears being provided with bayonet slots for cooperation with the aforementioned pins on said sleeve to permit the cap to normally cover the upper end of the valve stem, and further permit the outward swinging movement of the cap with respect to the sleeve for uncovering the upper end of the valve stem for inflating purposes.

2. A dust cap comprising a sleeve threaded at its lower end on the usual valve stem, laterally extending pins at diametrically opposite points on the upper portion of the sleeve, a cap member, ears on the lower portion of the cap at diametrically opposite points, said ears being provided with bayonet slots for cooperation with the aforementioned pins on said sleeve to permit the cap to normally cover the upper end of the valve stem, and further permit the outward swinging movement of the cap with respect to the sleeve for uncovering the upper end of the valve stem for inflating purposes, and means in said cap for engagement with the upper end of the valve stem when the cap is in its normal position.

In testimony whereof we affix our signatures.

EMANUEL NELSON.

ADOLPHUS ADDISON BASSETT.
